Application filed March 9, 1899. Serial No. 708,447. Term of patent 14 years.

To all whom it may concern:

Be it known that I, SPENCER A. 5 In the said drawing my design is represented in side view.

The design consists in the representation of a human leg and foot in connection with

the head proper of the machine, the leg *a* being shown flexed at a right angle, the thigh portion being vertical and the shank horizontal, and the foot *b* projected upward alongside the head proper.

What I claim is—
